JOINTED FLUORESCENT LAMP FIXTURE
WHICH MAY BE COLLAPSED FOR SHIP-
MENTLouis Mided and Henry C. Gorden, Chicago, Ill.,
assignors to Good Manufacturing Company,
Inc., Chicago, Ill., a corporation of Illinois

Application March 18, 1947, Serial No. 735,454

13 Claims. (Cl. 240—51.11)

1

This invention relates in general to an electric lighting fixture of the straight fluorescent tube type and is more particularly described as a fixture of this class which is foldable for compactly storing and shipping it.

Electric lighting fixtures for the straight forms of fluorescent lamps are necessarily long to accommodate the longer lamps and if they are intended to receive a plurality of lamps, the fixture parts for supporting the lamps are bulky and cumbersome both for storage and for shipment.

The present invention relates more particularly to fixture supporting parts which are foldable when not in use, for storage and shipment, into a compact package. The foldable parts are directly hinged to an intermediate part so that they may be easily extended by simply unfolding them for the reception of the lamps and to place the fixture in use.

An important object of the invention is to provide an electric lighting fixture for straight tubular lamps which has parts foldable together for compactly storing and shipping the fixture parts exclusive of the lamps.

A further object of the invention is to provide a foldable electric lighting fixture for straight tubular lamps in which each of the lamp supporting heads is hinged to one end of an intermediate part, the head of that part folding over the opposite end of the intermediate part.

A further object of the invention is to provide an electric lighting fixture for straight tubular lamps having lamp supporting heads with recesses at the top for inserting tubular lamps therein without danger of the lamps falling from the supporting heads either in attaching or releasing them therefrom.

A further object of the invention is to provide an electric lighting fixture having a central supporting portion with tubular lamps hinged thereto and extensible in opposite directions with a top plate hinged to the central supporting portion and attachable to a ceiling lighting fixture so that access may be had to the supporting part of the fixture while it is suspended in open position from the ceiling plate.

A further object of the invention is to provide a foldable electric lighting fixture with tubular lamp supporting heads and each head having an attachable end piece extending over the head and holding it in place, the end piece being removable for placing similar fixtures close together in alignment and to uncover a knock-out opening for interconnection of conductors between adjacent fixtures for controlling their lighting.

2

Other objects of the invention will appear in the specification and will be apparent from the accompanying drawings in which,

Fig. 1 is a top view of an electric lighting fixture in accordance with this invention;

Fig. 2 is a longitudinal sectional view of the fixture shown in Fig. 1;

Fig. 3 is a bottom view of the fixture parts without the lamps in folded relation;

Fig. 4 is a side view of the parts in an upside down position as shown in Fig. 3;

Fig. 5 is a sectional detail showing the location of the parts in folded upside down relation as taken on the line 5—5 of Fig. 4;

15 Fig. 6 is a sectional view of the supporting part of the fixture in hinged relation to the cover plate as taken on the line 6—6 of Fig. 2.

Many different electric lighting fixtures for straight tubular lamps are now produced in which the lamps are variously mounted in heads slightly longer than the length of the tubular lamps with accompanying, intermediate or supporting structure which is substantially coincident in length with the lamps and the heads. This requires not only a heavy and cumbersome lamp supporting structure, but also, it necessitates a container of large size for receiving, shipping and storing the fixture parts.

The present invention overcomes these objections by mounting all of the necessary transformers, ballasts and contact makers in a relatively short, intermediate, supporting container and in hinging each of the lamp supporting heads near one end of the intermediate support so that when folded, it swings over the opposite end of the intermediate support. This produces a compact structure when folded which requires a container of much less size which is more easily stored and shipped.

40 Referring now more particularly to the drawings, this fixture comprises a central or intermediate hollow support 10 preferably made of sheet metal and having a cover 11 connected thereto at one side by hinges 12. In the cover

45 is a central opening 13 for a fixture stud, and side openings 14 for conductor wires, and opposite the hinges is a flange 15 through which fastening screws 16 may be inserted into the corresponding edge of the support 10 for holding them together.

50 With this construction, the cover 11 may be disengaged from the remainder of the fixture and attached to the fixture stem in a ceiling and then the supporting parts may be attached thereto by connecting the hinges of the hollow support

thereto, leaving the parts in a partially open position as indicated in Fig. 6 so that wiring connections and other adjustments may be made before the support is closed against the cover and held in place by the fastening screw 16.

Projecting from the bottom of the support 10 is an angular rib 11 with an opening 18 at each end of the rim in the bottom of the container and at one side of the rib.

A hollow triangular bar 20 of sheet metal is connected to one side of the triangular rib near each end thereof by a hinge 21, the hinges for opposite bars 20 being at opposite sides of the rib and at opposite ends thereof so that each bar will swing from a position against one side of the triangular rib as shown in Figs. 3 and 4 to an extended position at the opposite end as shown in Figs. 1 and 2.

Near the hinged end of each hollow bar 20 is an opening 22 which registers with the corresponding opening 18 in the bottom of the container when the hollow bar is in extended position so that communication is afforded between the hollow bar and the interior of the support 10 for the passage and insertion of electrical conductors. At the end of each opening 22 opposite the hinge is an outwardly turned projection 23 which is located to extend outside of the end of the support 10 when the bar is in extended position so that a fastening screw 24 may be inserted through the projection and through the adjacent wall of the support to hold the hollow bar in its extended position.

At the outer end of each hollow bar 20 is a lamp supporting head 25 which extends crosswise of the supporting bar and is provided with a plurality of sockets 26 for receiving the end contacts of a corresponding plurality of lamps 27. The sockets are disposed within the heads, each of which has a flange 28 at the bottom for receiving the end of the lamp therein so it will not fall from the fixture even though disengaged from the socket. The upper edge of each head is formed with a recess 29 between adjacent sockets so that each lamp may be inserted through the recess 29 in the opposite ends and engaged with the sockets in the opposite heads 25.

To secure each head 25 in position at the end of the hollow supporting bar 20, a clamp 30 has a hook 31 at one end adapted to be inserted through an opening 32 in the hollow bar 20 to extend around the outside of the head 25 and with a flange 33 at its other end adapted to extend over the opposite or uppermost end of the bar 20 when extended, and a fastening screw 34 inserted through the flange and into the wall of the hollow bar. With this construction, each head 25 is held firmly in position against tilting movement relative to its supporting hollow bar 20, and the outer ends of the heads are not movable angularly to dislodge the lamps when inserted in and supported by the heads.

When it is desired to place a number of these lighting fixtures close together in alignment, the end clamps may be omitted and the heads 25 secured only by a fastening screw, leaving the heads of adjacent fixtures close together. For this arrangement, that portion of each head which is covered by the clamp may be provided with a knock-out disc 35 partially connected to the head which may be removed for affording communication between the adjacent fixtures through their hollow supporting bars 20, the knockout being located at the end of the hollow bar.

With this construction, the fixture is stored and shipped in its collapsed position, thereby requiring containers which are only about one-half the size of those required for the ordinary fixture supports or the lamps of the same size. In either event, the lamps are separately supplied and are neither shipped nor stored with the fixture supporting parts.

Heretofore in installing a lighting fixture, two men are usually necessary since the fixture is too heavy for one man to hold and make the connections while securing it to the wall or to a suitable fixture supporting stem. In the present case, the fixture supporting cover is attached to the fixture stud or other ceiling support, the remaining portion of the fixture including the support 10 is hooked upon the cover 11 by means of the hinges 12 by one man who then makes the necessary circuit connections. The supporting hollow bars 20 may then be extended and fastened securely in place after which the lamps are inserted from the top through the recesses 29 without danger of dropping the lamps even though they are not engaged in the sockets.

The details of the conductors, transformers, ballasts or other lighting fixture parts are not necessary to the understanding of this invention and may be of any ordinary or standard construction and arrangement. The container support 10 and the hollow bars 20 are sufficiently large to receive these parts and to form ample space for connecting and storing them.

Although the preferred construction of this lighting fixture has been described in some detail, it should be regarded as an illustration and not as a limitation of the invention, as various changes in the construction, combination and arrangement of the parts may be made without departing from the spirit and scope of the invention.

We claim:

1. An electric lighting fixture for straight tubular lamps, comprising an intermediate support less in length than the lamps therefor, a pair of heads for engaging the opposite end of each lamp, and means connecting each head to swing upon the support and over the opposite end of the support in compactly folding the fixture parts.

2. An electric lighting fixture for straight tubular lamps, comprising a pair of lamp supporting heads, an arm extending from each head, a central support to which each arm is hinged so that the arm will swing against the support in folding the head over the opposite end of the support.

3. An electric lighting fixture for straight tubular lamps, comprising a pair of lamp supporting heads, an arm attached to each of the heads, an intermediate support to which each arm is hinged, the hinge of one arm being at an angle to the hinge of the other arm so that each head will fold over the opposite end of the support free and clear of the other head and substantially parallel thereto.

4. In an electric lighting fixture for straight tubular lamps, a pair of lamp supporting heads, a hollow arm connected to each head, an intermediate support having a rib with webs at an angle to each other to each of which one of the arms is pivoted, one hinge being on the rib at an angle to the other hinge, and the arms being foldable oppositely to fold the head over the opposite end of the support and adjacent thereto in compactly folding the said fixture parts.

5. An electric lighting fixture for straight tu-

tular lamps, comprising a pair of lamp supporting heads, a hollow arm connected to each head, an intermediate support having a projecting rib with webs at an angle to each other to each of which one of the arms is hinged, one hinge being at an angle to the other hinge and the arms being foldable oppositely so that each head will extend over the opposite end of the support and at right angles to its extended position with respect to the support.

6. An electric lighting fixture for straight tubular lamps, comprising a pair of lamp supporting heads, a hollow arm attached to each of the heads, an intermediate support to which each of the arms is hinged for folding it thereon, the hinge connection for one arm being spaced inwardly from the adjacent end of the support when the arm and head are extended, and the pivoted end of the arm and the adjacent end of the support having openings which register when the arm is in extended position.

7. In an electric lighting fixture for straight tubular lamps, a pair of lamp supporting heads, a hollow arm connected to each head, an intermediate support having a rib with webs at an angle to each other to one side of which each of the arms is pivoted near one end to swing oppositely over the other end in folding and to swing outwardly from the hinged end in extending the fixture, the support and the arm having openings which register when the fixture head is extended to receive electrical conductors for the lamp heads therein.

8. In an electric lighting fixture for straight tubular lamps, a pair of lamp supporting heads, an arm attached at one end to each head, an intermediate support to which the other end of each arm is pivoted near the end of the support so that the arm will swing over the support in folding and will project at the other end when unfolded, each head having a plurality of lamp sockets disposed within the heads and with a bottom retaining flange and an upper recessed edge in each head when the heads are in horizontal lamp supporting position, the recesses providing means for inserting lamps from the top of the heads and the lower flange holding the lamps in position in the heads when they are removed from the sockets.

9. An electric lighting fixture for straight tubular lamps, comprising a pair of lamp supporting heads, an arm attached to each of the heads, an intermediate support to which each arm is hinged near the end of the support so that the head will fold over the opposite end of the support and will project oppositely from the end of the support to which it is hinged, the arm having an outwardly turned projection for engaging outside of the end of the support when in extended position, and fastening means for connecting the projection to the adjacent end of the support in extended position.

10. In an electric lighting fixture for straight tubular lamps, a pair of lamp supporting heads, a

hollow arm connected to each head, an intermediate support having a projecting rib with webs at an angle to each other to each of which one of the arms is hinged, one hinge being on the web at one side of the rib and the other hinge being on the web at the other side of the rib adjacent opposite ends of the support, the hinged arms being foldable against the rib to project each head over the opposite end of the support, and the arms being aligned with the rib when the heads are moved to their extended positions.

11. In an electric lighting fixture for straight tubular lamps, a pair of lamp supporting heads, an arm connected at one end to each head, an intermediate support to which the other end of each arm is hinged so that the arm will swing against the support in folding the head over the opposite end of the support, the support having a cover connected thereto by hinges at one side thereof, and fastening means at the other side of the cover for engaging the opposite side of the support, and fixture fastening means in the cover whereby the cover may be attached to a ceiling fixture and the support with the heads and arms connected thereto may be mounted by the cover hinges so that the support will swing open from the cover at the under side thereof.

12. In an electric lighting fixture for straight tubular lamps according to claim 11, with a clamp for the head having a hook at one end extending through the head, the clamp extending around the outer side of the head and having a top flange, and means for securing the flange to the upper side of the arm.

13. In an electric lighting fixture for straight tubular lamps according to claim 11, with a clamp extending over the outer end of each head having a hook extending through the head at the bottom and a flange overlying the arm at the top, and means securing the flange to the outer end of the arm and binding the head in place, the tubular lamps being inserted between the heads in their extended positions.
